COMBINATION GUN AND CAMERA

Owen W. Atkin, West Los Angeles, and Philip Fisher, Ocean Park, Calif.

Application October 30, 1936, Serial No. 108,406

2 Claims. (Cl. 88—17)

Our invention relates to firearms, and more particularly to a firearm, such, for example, as a pistol or revolver, having incorporated therein camera means for photographing objects at which the firearm is aimed.

This application is a continuation-in-part of our copending application entitled Camera attachment for firearms, Serial No. 24,942, filed June 4, 1935.

Although our invention has a valuable use in various arts, industries, and sports, it is especially valuable for police work. By the use of this invention a photographic record may be obtained of any criminal or other person at which the firearm is aimed or discharged, which record is extremely valuable in case of escape.

It is an object of our invention to provide a firearm which includes a motion picture mechanism operatively connected to the firearm, and which enables the taking of a motion picture of the person aimed at. This enables the obtaining of a permanent record of the person's appearance and also his characteristic actions, both of which are valuable for purposes of identification.

It is an object of our invention to provide a firearm incorporating the features pointed out heretofore, or part of them, in which the control means which controls the operation of the motion picture mechanism may be operated with the trigger finger of the person using the firearm and will not in any way interfere with the normal or usual operation or handling of the firearm.

The photographic record which may be obtained by the use of our invention is valuable as evidence to prove the perpetration of a crime. If a criminal is caught in the act and a picture of his actions is taken before firing the pistol, during the firing of the pistol, and after the firing of the pistol, or without firing the pistol, a record is obtained which may be very useful in court.

It is an object of our invention to provide a pistol or revolver including motion picture mechanism operable in connection with the mechanism for firing the pistol, and which may be operated before, during, or after the firing of the pistol, or may be operated without firing the pistol, or may be continuously operated even though a series of shots are fired; and in which the operation of the motion picture mechanism does not interfere with the normal or customary use of the firearm.

It is an object of our invention to provide for incorporation in a pistol a motion picture mech-

anism which may be associated with the pistol without disturbing its balance, without interfering with the aiming or firing of the pistol, which will not interfere with the removal or the insertion of the pistol in the ordinary holster, and which is compactly arranged below the barrel in the triangular space positioned below the barrel and ahead of the trigger guard.

It is a further object of our invention to provide a firearm of the character pointed out heretofore including a motion picture mechanism which is simple and compact in its design, which is readily attachable to pistols already in use, or which may be built into new pistols, in which the parts are uniquely arranged so that they may be operatively connected to the pistol and adapted for operation with or independent of the trigger of the pistol.

It is a further object of our invention to provide a construction of the character pointed out in the preceding paragraph in which a motor is provided which operates the film advancing mechanism and shutter and has separate drive means for operating the take-up spool on which the film is wound after exposure.

A still further object of our invention is to provide a firearm as pointed out heretofore in which the spools carrying the unexposed and the exposed film and the control means which controls the operation of the motion picture mechanism are located to the rear, and the film advancing and shutter mechanism is located in front of the motor.

It is a further object of our invention to provide a construction in which all of the working parts are mounted on a plate and may be installed as a unit in the light proof case of the invention, and in which the various parts are operated through a chain of gears mounted adjacent said plate.

The preferred form of our invention to be disclosed herein is the result of a large amount of development work and design and there are additional objects and advantages of our invention which are so numerous that they will be pointed out in the course of the following description.

For the purpose of illustrating our invention to those skilled in the art we have selected a preferred form of our invention. It should be understood, however, that various alterations and modifications may be made without departing from the spirit and scope of our invention, and, therefore, we do not wish our patent protection to be limited to the details de-

scribed herein but intend that the invention shall be broadly construed both as to its entire combination and subcombinations in accordance with the appended claims.

5 Referring to the drawings:

Fig. 1 is an elevational view of a firearm incorporating the features of our invention.

Fig. 2 is an elevational view taken as indicated by the arrow 2 of Fig. 1.

10 Fig. 3 is a longitudinal sectional view which forms a part of our invention, which view is taken on the line 3—3 of Fig. 2.

Figs. 4 to 7 inclusive are fragmentary sectional views taken on the lines 4—4 to 7—7 of Fig. 3.

15 Fig. 8 is a fragmentary view of the release means which forms a part of the control means for controlling the operation of the camera mechanism.

Fig. 9 is a section taken on the line 9—9 of Fig. 5.

The firearm of our invention in the preferred form illustrated herein includes a pistol having a barrel 11, a body 12, a grip or handle 14, a trigger 15 operatively connected to the mechanism which 25 operates the hammer 16, and further includes a trigger guard 17, which parts, of course, are in accordance with standard firearm construction. Adapted to be secured to the pistol is a case generally designated by the numeral 19, which case 30 includes a housing 20 and a cover 21 hinged at 22 to the housing 20 and releasably locked in closed position by means of a snap lock 23. The case is shaped so that it may fit in the triangular space which is formed below the barrel 11 and in 35 front of the body 12 and finger guard 17. The case, as will be noted, is shaped at 24 to closely fit these parts and to provide a recess for receiving the shell-ejection plunger 25. The upper wall of the housing 20 is provided with an attaching 40 means in the form of a semi-cylindrical member 26 which is shaped to fit around the barrel 11. The forward part of the housing supports a camera lens 27. The attaching means 26 and the lens 27 are preferably in accurate alignment so 45 that the lens is supported parallel to the axis of the barrel 11 with respect to a vertical plane. With respect to a horizontal plane, the axes of the barrel and lens may converge to meet at any point a distance from the muzzle of the pistol. To hold 50 the housing an additional attaching means, such as a screw 28 which screws into the body 12, may be provided.

Adapted to be secured to the side wall of the case 19 is a mounting plate 30, there being suitable screws 31 provided for this purpose. This mounting plate 30 supports the motion picture mechanism which may be assembled on the mounting plate and thereafter installed as a unit in the case 19. This mounting plate 30 supports 55 various shafts which in turn carry gears, spools, and other parts of the apparatus which will now be described.

Our invention provides a motor 35 which includes a central shaft 36 supported by the mounting plate 30 and a shell 37 which encloses a coil spring or clock spring 38. The inner end of this spring 38 is connected to the shaft 36, and the outer end thereof is connected to the shell 37. 60 By rotating the shell 37 in an anti-clockwise direction the spring may be wound up and thereafter tends to drive the shell of the motor in a clockwise direction. The motor 35 also includes a drive gear 39 which is mounted between the 65 shell 37 and the mounting plate 30, which gear

drives the various parts of the motion picture mechanism.

Secured to the mounting plate 30 in a position ahead of the motor 35 in a plane extending perpendicular to the axis of the lens 27 is an aperture plate 41 having an aperture 42 through which the frames of the film handled by the mechanism may be exposed. Positioned in the case to the rear of the motor 35 and secured to the mounting plate 30 is a shaft 44 which supports a light guard 45 adapted to enclose a raw-film spool 46. The light guard 45 includes a base 47 detachably connected to the mounting plate 30 by aligning pins 48 and having a mouth 49 through which the raw film, as indicated 50, may be extended forwardly over the guide roller 51 downwardly along the rear face of the aperture plate 41 under a guide roller 52 and rearwardly to a take-up spool 53, the film 50 being held against the rear face of the aperture plate 41 by means of a pressure plate 54. The size of the film in the form of our invention is 16 mm., and the spools will accommodate 5 feet of film with 48 frames to the foot.

The take-up spool 53 is removably supported on a shaft 57 secured to the mounting plate 30 and has a gear 58 positioned adjacent the mounting plate 30 whereby the take-up spool may be rotated in a clockwise direction. This take-up spool 58 is mounted in an extreme rearward position at the lower part of the case and is driven through a chain of gears 59, 60, 61, and 62, the gears 59 and 60 being rotatable on a shaft 63, the gear 61 being rotatable on a shaft 64, and the gear 62 being rotatable on a shaft 65, which shafts are mounted on the mounting plate 30. The chain of gears just mentioned is driven by engagement of the drive gear 39 with the gear 59.

A control means is provided by our invention whereby the mechanism may be set into operation. This control means in the form of our invention disclosed herein includes an auxiliary trigger 70, the lower end of which is pivoted at

the lower end of the trigger 15 of the pistol on a pivot pin 71. This auxiliary trigger is, as shown, positioned in front of the trigger 15, and the trigger finger of the person using the pistol engages the auxiliary trigger 70 and the first action which occurs is the movement of the auxiliary trigger 70 rearwardly into a position indicated by dotted lines 72, at which time the pressure is transmitted to the trigger 15 and thereafter the auxiliary trigger and the trigger move rearwardly together in order to discharge the firearm.

The upper end of the auxiliary trigger has a connecting means in the form of a small wire or rod 73 connected to it in any suitable manner, such as by a lock screw 74. This connecting means 73 extends forwardly through an opening 76 formed in the trigger guard 17, through an opening 77 formed in the case 19, and into the interior of the case. The forward part of the connecting means includes a coil spring 78 and is connected to the upper end of an operating lever 79 which is pivoted on a shaft 80, which shaft 80 is mounted on the mounting plate 30. Pivotally supported on a shaft 83 which is mounted on the mounting plate 30 is a pawl 84 which extends downwardly and has a follower pin 85 supported at its lower end, which follower pin 85 extends outwardly through a slot 86 formed in the operating lever 79. The pawl 84 has a tooth 88 adapted to engage teeth of a ratchet wheel 89 which is connected to the gear 61. The pawl 84 is normally held in engagement with the ratchet wheel 89 by means of a coil spring 91 which sur-

rounds the shaft 33. In this manner the mechanism is held from operation, since the gear 61 is prevented from rotating, and since the gear 61 is connected through the gears 59 and 60 with the drive gear 39 of the motor 35. By moving the auxiliary trigger 70 rearwardly into dotted line position the pawl 88 is moved into a released position as shown in Fig. 8, and the ratchet wheel 89 is released, thus allowing the mechanism to operate.

For the purpose of controlling the speed at which the mechanism operates we provide a governor construction which is shown best in Fig. 6. Keyed to the shaft 61, so that it may move axially on the shaft but not rotate, is a friction plate 92 which is pressed into frictional engagement with the adjacent face of the ratchet wheel 89 by means of a compression spring 93. The amount of pressure exerted by the pressure plate 92 is determined by the position of the adjusting and lock nuts 94 which are threadedly positioned on the shaft 61. This governor means is preferably adjusted so that camera mechanism will operate to move the film at approximately 16 frames per second.

For the purpose of advancing the film with relation to the aperture 42, we provide film advancing mechanism which is illustrated best in Figs. 3, 5, and 9. Mounted on a shaft 100, which is supported by the mounting plate 30, is a plate 101 having an eccentric pivot 102 on which an advancing arm 103 is pivotally supported. The free end of the advancing arm 103 has a guide pin 104 which extends into a vertical slot 105 formed in a flange of the aperture plate 41. The upper rearward part of the arm 103 has a film engaging finger 106 which is adapted, during the operation of the apparatus, to extend into perforations of the film 58 and advance the film downwardly. When the plate 101 is rotated in its normal clockwise direction the operation of the arm 103 is as follows. As the upper end of the stroke is passed the lower end of the arm 103 moves forwardly and downwardly, while the upper end of the arm swings rearwardly and downwardly. This brings the film advancing finger 106 into a perforation on the film and engages the lower wall of the perforation so that as the rotation of the plate 101 continues the whole arm 103 moves downwardly, thus advancing the film. When the lower end of the stroke is reached, the lower end of the arm 103 moves rearwardly, which swings the upper end of the arm forwardly out of engagement with the film, and thereafter the arm moves upwardly out of contact with the film to its uppermost position, after which it again engages the film and the advancing operation is repeated. The film advancing mechanism is operated through a chain of gears 108, 109, and 110. The gears 108 and 109 are rotatable on a shaft 111 mounted on the mounting plate 30, while the gear 110 is formed integral with the plate 101. The gear 108 engages the drive gear 39 and is thus operated by the motor 35.

Our invention also provides a shutter mechanism whereby light is admitted to the frame of the film in alignment with the aperture 42 during the time that the film is stationary. The shutter, as shown in Figs. 3 and 4, is in the form of a hollow cylinder 112 having two openings 114 arranged on opposite sides of the cylinder. This cylinder is rotatable on a shaft 115 which is mounted on the mounting plate 30. Connected to the shutter 112 is a gear 116 which meshes with

an idler gear 117 which is rotatable on a shaft 118 and which is engaged by the gear 110. It will be seen, therefore, that the actions of the film advancing mechanism and the shutter are correlated. Figs. 3 and 4 show the position of the parts just as the film has been disengaged at the lower end of the stroke of the film advancing mechanism. During the time that the film is moved the openings 114 are disaligned with the lens 27 and no light reaches the film. Surrounding the shutter 112 is a light shield 120 which, on the rearward part, has a rectangular light conduit 121 which extends to the aperture 42. This directs any light which passes through the lens 27 to the aperture 44. The light shield 15 is secured to the mounting plate 30 by screws 123 extending through ears 124 of the light shield.

The motion picture mechanism is especially designed for compactness and light weight so that it may be secured in the triangular space 20 below the gun barrel 11 where it will not interfere with the normal use of the pistol and not materially add to its weight.

In the use of our invention a spool of raw film is placed in the light guard 45 with the emulsion 23 on the outer side of the film and is extended forwardly over the roller 51, downwardly between the aperture plate 41 and the pressure plate 54, below the roller 52, and rearwardly to the take-up spool 53 where it is connected to the hub 30 thereof. A small amount of slack is left, as indicated at 125, to assure the film will not be injured, since the take-up spool 53 is continuously rotated while the film is intermittently advanced across the aperture 42. However, the film advancing mechanism, which moves the film only during half of its rotation, is geared to operate or rotate twice as fast as the take-up spool so that the advancing mechanism advances the film sufficiently to permit the winding of the film 40 thereon without injury to the film. Furthermore, as the film is wound onto the take-up spool 53 the diameter increases, but the film advancing mechanism advances the film sufficiently to compensate for this. After the film has been threaded through the apparatus as explained, the cover 21 is, of course, closed so that the interior of the case is protected from the light.

When it is desired to use the gun it is held in the hand of the person using same in the ordinary fashion, and the trigger finger instead of engaging the trigger 15 engages the auxiliary trigger 70. When it is desired to make a photographic record the user of the gun depresses the auxiliary trigger 70, moving it rearwardly into a position indicated by dotted lines 72 of Fig. 3. This swings the lever 79 rearwardly and the pawl 84 is disengaged from the ratchet wheel 89. This releases the mechanism and the motor 35 is free to drive the various gears which sets the motion picture mechanism in operation, the speed thereof being controlled by the governor illustrated in Fig. 6. The film advancing mechanism intermittently advances the film, as previously pointed out, and thus brings consecutive frames into position for exposure before the aperture 42. The shutter 112 is operated as previously explained and transmits light to the frame of the film adjacent the aperture 42 during the time that the film is stationary.

It will be seen that the motion picture mechanism may be operated without discharging the gun. However, if it is desired to discharge the gun, the trigger finger is pulled rearwardly a greater distance and the trigger 15 is pulled

rearwardly, thus operating the hammer and firing a shot. The trigger 15 may then be allowed to return to its original position without, however, releasing the auxiliary trigger 70, and the motion picture mechanism may therefore continue to operate. In this manner one or a series of shots may be fired while maintaining the motion picture mechanism in operation. It is quite apparent from the foregoing that it is possible to continuously operate the motion picture mechanism either with or without discharging the gun.

It is believed that from the foregoing detailed description the mode and manner in which the various objects of our invention have been accomplished are quite evident and that the preferred form of our invention herein described and illustrated is susceptible of alteration and modification without departing from the spirit and scope of the invention which are defined by the accompanying claims.

We claim as our invention:

1. A combination firearm and motion picture photographic apparatus including a trigger on said firearm, a supplementary trigger pivoted to said firearm trigger at one end thereof and lying along and normally spaced forwardly therefrom, and means connecting the other end of said supplementary trigger to said photographic apparatus whereby when the supplementary trigger is

pressed the photographic apparatus will be actuated to cause pictures to be taken and further actuation of said supplementary trigger will cause actuation of said firearm trigger to discharge the firearm.

2. A device of the class described, comprising the combination of: a pistol having a barrel, body portion, a trigger and a trigger guard; a light proof case secured to said pistol in a position below said barrel, said light proof case being of triangular shape to fill the triangular space below the barrel and in front of the body and the trigger guard; motion picture photographic mechanism having a pawl device to control the operation thereof whereby a motion picture can be taken of an object aimed at; and a supplementary trigger pivoted at one end to the end of said pistol trigger lying along and normally spaced forwardly therefrom, and means connecting the other end of said supplementary trigger to the pawl device of said motion picture mechanism whereby when the supplementary trigger is pressed the motion picture apparatus will be actuated to cause pictures to be taken and further actuation of said supplementary trigger will cause the actuation of said pistol trigger to discharge said pistol.

OWEN W. ATKIN.
PHILIP FISHER.
